REGENERATIVE OVEN

Carl Otto, Essen, Germany

Application April 24, 1933, Serial No. 667,585
In Germany January 23, 1932

7 Claims. (Cl. 202—143)

The invention relates to chamber ovens operating with regenerators, more particularly ovens intended for the production of coke and gas, in which the regenerators serving for preheating the media of combustion, viz. air or gas and air, and those taking up the heat of the waste gases are arranged in parallel to one another alternatively in the same row. The invention has for its object to avoid the transition of preheated air or preheated gas from the preheating regenerators to the waste heat regenerators, which object is obtained by a new and peculiar construction of the partitions existing between the regenerators which are fed in opposite direction. This object is achieved according to the invention by vertical chambers being provided in the regenerator partitions which chambers are closed at bottom and terminate somewhat below the upper edge of the regenerators. They are filled with a refractory mass which has but little or no tendency to agglomerate or form bead like masses. In ovens of a design in which a gas not to be preheated (strong gas) is supplied through passages which vertically extend in the regenerator partitions and directly open into the individual heating flues of the oven chambers, the said vertical chambers are disposed between the gas supply passages, seen in the longitudinal direction of the partition. The refractory mass the vertical chambers are filled with must not conglomerate nor have the tendency to purling, in a degree as for instance ordinary, not disintegrated sand. Furthermore, the mass either has to be in a burnt out state, such as for instance burnt clay (fire clay) or to have the consistency of certain dry mortar mixtures. At any rate the mass must not undergo changes in structure when exposed to the temperatures prevailing in the regenerators. The desired avoidance of an agglomerating tendency is obtained best by an extremely fine grain which is achieved in a satisfactory degree by using burnt fire clay, dry mortar mixtures or sand, and results in a considerable increase of the surface and thus in an effective adhesion. This fine grained mass is poured into the vertical chambers already in the erection of the ovens and permanently remains therein. When a joint occurs that communicates with a vertical chamber, the mass enters it from the chamber and tightens it, but in so doing the mass is consumed to some extent. Therefore, it is desirable to provide the possibility of re-filling the chambers with the fine grained mass. To this end an aperture leading to one of the adjacent regenerators is pro-

vided on the upper end of the vertical chambers which aperture can be closed by means of a plug. In ovens where vertical strong gas channels are arranged in the same regenerator partition, the vertical chambers according to the invention may be in permanent or temporary communication with an adjacent one of these strong gas channels through an inclined passage rising toward the channel. 5

The effect of the vertical chambers of the invention may be increased still by providing a stone bond in which the vertical chambers are formed by two vertical rows of bricks which form between them a joint extending in parallel with the longitudinal direction of the partitions. Consequently, upon leakage of this joint the mass contained in the vertical chambers cannot penetrate yet in the regenerators and obstruct them. In order to further exclude this possibility, the joint running in the longitudinal direction of the partition which is between the two rows of bricks that form a chamber between them, may meet transverse joints which likewise do not run up to the partitions of the regenerators. 10 20

When joints occur in the partitions of the regenerators under the action of the pushing and shearing forces the regenerator brickwork is exposed to in service, these joints, immaterially whether horizontal or vertical, fill themselves with the mass contained in the vertical chambers 25 without this mass, provided it has the suitable nature, being capable to advance up to the regenerator chambers. The provision of the vertical chambers in the regenerator partitions therefore affords a reliable protection from the transition 30 of preheated gas or preheated air to the waste heat regenerators and allows in designing ovens of the type under consideration to make these partitions comparatively thin, as a result of which a larger number of regenerators may be 35 provided or the height of the oven brickwork reduced. 40

In order that the invention may be clearly understood and readily carried into effect, two embodiments of the invention are illustrated by way 45 of example in the accompanying drawing as applied to regenerative chamber ovens. In the first embodiment the vertical chambers provided in the partitions between the regenerators and extending between the strong gas channels communicate with an adjacent strong gas channel, whilst in the other embodiment they communicate with adjacent parts of regenerator chambers. 50 55

In the drawing

Figures 1a to 1c are vertical sections of a regenerator partition in its longitudinal direction on line I—I of Figures 2a to 2c, Figure 1a and 1c showing the first embodiment and Figure 1b the other embodiment.

Figures 2a and 2c relate to the first and

Figure 2b to the other embodiment and are horizontal sections of the regenerators on lines 10 A—A, B—B and C—C of Figures 1a to 1c.

Figure 3 relates to the other embodiment and is a vertical section normal to that represented in Figure 1b, on line III—III of Figure 2b.

Referring to this drawing, *a* denotes the regenerator chambers which are arranged in parallel in a row in the longitudinal direction of an oven battery. *b*, Figure 3, are passages connecting the regenerators with the rows of heating flues *c* alternating with the coking chambers *d*. Each 20 two regenerator chambers *a* serving to preheat the media of combustion (weak gas and air) alternate in the longitudinal direction of the battery with two regenerators *a* which take up the heat of the waste gases. Upon reversal of the draft, the regenerators exchange their action. Therefore, in the two different stages of operation of the ovens a preheating regenerator space exists on the one side of the partition *e* and on the other side a waste heat regenerator chamber.

30 The partitions *e* include in a manner known in itself vertical gas supply channels *f* formed by bricks *g* of square section, see Figure 2a, and opening into the burners *h* which project into the heating flues. The bricks *i*₁ and *i*₂ adjacent to the bricks *g* form between them vertical chambers *k* which are filled with the refractory non-agglomerated mass described above. The vertical joint existing between the bricks *i*₁ and *i*₂ and running in the longitudinal direction of the partitions *e* at its ends meets transverse joints which owing to the peculiar design of the bricks of the bond do not immediately run up to the adjacent regenerator chambers *a* so that the mass entering from the vertical chambers *k* the joint obstructs the latter and prevents transition of gas and air, but cannot enter the regenerator itself. In the embodiment illustrated in Figures 1a, 1c and 2c the vertical chambers *k* by inclined passages *m* communicate with an adjacent strong gas channel. Hence, the mass can be re-filled into the chambers *k* even during the operation of the oven.

In the other embodiment illustrated in Figures 1b, 2b and 3 a connecting passage *n* extends from the top of the chambers *k* to an adjacent regenerator chamber and is closed by a plug *o* during the operation of the oven. When the brickwork of the regenerators is re-bult, the plugs *o* temporarily may be withdrawn and the chambers *k* re-filled with the mass.

I claim:

1. A regenerative oven of the class described comprising a plurality of regenerators and masonry partition walls each separating two ad-

5 jacent regenerators in which the gas pressures are normally different and each formed with vertical chambers closed at their lower ends, and a fine grained mass of granular refractory material in each of said chambers.

2. A regenerative oven of the class described comprising a plurality of elongated regenerators arranged side by side and elongated masonry partition walls each separating two adjacent regenerators in which the gas pressures are normally different and heating walls one above and extending longitudinally of each of said partition walls and containing flues distributed longitudinally of said wall, each of said partition walls being formed with a plurality of vertically disposed gas supply channels distributed along the length of the wall, and communicating with the flues of the heating wall above it, and being formed with vertical chambers closed at their lower ends and alternating with said channels along the length 10 of the partition wall, and a fine grained mass of granular refractory material in each of said chambers.

15 3. An oven as specified in claim 1 in which each of the said partition walls is formed with passages 25 each connecting a chamber in said wall to an adjacent regenerator, and in which removable blocks normally close said passages.

20 4. An oven as specified in claim 2 in which the upper ends of the chambers in each partition wall 30 do not extend upward above the tops of the adjacent regenerators, and in which each partition wall is formed with passages each extending upwardly at an angle to the horizontal from the top of a chamber with which it communicates and connecting the latter to an adjacent gas supply channel, whereby said chambers may be refilled with said granular material through said channels and passages.

35 5. An oven as specified in claim 1 in which the fine grained mass of granular refractory material 40 consists of fine burnt fireclay particles.

45 6. A coke oven as specified in claim 1 in which each partition wall comprises two piles of bricks forming the walls of each of the vertical chambers containing the granular material, and in 45 which the joints between the bricks in one, and the bricks in the other of said two piles extend in a direction parallel to the sides of the wall facing the adjacent regenerators.

50 7. An oven as specified in claim 1 in which each regenerator partition wall is formed of bricks comprising two piles of bricks forming the walls of each of the vertical chambers containing the granular material and in which the joints between the bricks in one, and the bricks in the other of said two piles extend in a direction parallel to the sides of the wall facing the adjacent regenerators, said wall also comprising bricks providing joints which are transverse to the first mentioned joints at the ends of the latter and 55 terminate short of said faces.

CARL OTTO.
